UNITED STATES PATENT OFFICE.

JOHN BATH, OF WORCESTER, MASSACHUSETTS.

THREAD-GRINDING MACHINE.

Application filed December 27, 1921, Serial No. 524,817. Renewed August 1, 1927.

This invention relates to a machine particularly designed for grinding the threads of taps, thread gages or other similar articles.

5 It is one object of my invention to provide a thread grinding machine and a method of using the same by which the grinding operation may be made substantially continuous during the travel of the grinding wheel 10 in both directions. With this object in view, an important feature of my invention relates to the provision of an improved device for engaging and driving the work, said device being capable of definite angular adjustments to compensate for back lash and for 15 other desired purposes.

A second object of my invention is to provide a machine in which the work spindle is directly driven and in which the lead screw 20 for the grinding wheel is positively driven from the spindle.

An important feature of my invention relates to the provision of a plurality of interchangeable master lead screws by which 25 threads of different pitch may be ground. Other features of my invention relate to improved means for accurately forming and dressing the face of the grinding wheel, to means for accurately determining the 30 amount of back lash in the machine, to an improved table adjustment, both angularly and longitudinally, to an arrangement for distributing the wear on the lead screw and for adapting the machine to operate on 35 taps having shanks of different lengths, to arrangements and combinations of parts which will be hereinafter described and more particularly pointed out in the appended 40 claims.

A preferred form of my invention is shown in the drawings, in which

Fig. 1 is a plan view of my improved machine;

45 Fig. 2 is a horizontal sectional view of the work driving head;

Fig. 3 is a front elevation of the wheel head;

50 Fig. 4 is a plan view of the work table and certain parts carried thereby;

Fig. 5 is an end view of the work table;

Fig. 6 is a detail sectional plan view of the mechanism for angularly adjusting the table;

55 Fig. 7 is a front elevation of the devices for longitudinally adjusting the table;

Fig. 8 is an end elevation of the face plate and work driving attachments;

Fig. 9 is a sectional elevation taken along the line 9—9 in Fig. 8;

Fig. 10 is a partial plan view looking in the direction of the arrow 10 in Fig. 9;

Figs. 11, 12, 13, and 14 are detail sectional views taken respectively along the lines 11—11, 12—12, 13—13, 14—14, of 65 Fig. 8;

Fig. 15 is a plan view of certain parts of the machine, illustrating the method and apparatus by which the amount of back lash is determined;

Fig. 16 is a detail sectional elevation taken along the line 16—16 in Fig. 15;

Fig. 17 is an end elevation looking in the direction of the arrow 17 in Fig. 15;

Fig. 18 is a partial plan view of certain 75 parts, including my improved wheel dressing device, the tail stock being shown in section;

Fig. 19 is a detail plan view illustrating the use of the wheel dressing device;

Fig. 20 is an end elevation of the wheel dressing device, and shows the auxiliary tool for dressing the face of the wheel;

Fig. 21 is a plan view of the auxiliary tool;

Fig. 22 is an end view of the tail stock, looking in the direction of the arrow 22 in Fig. 18, and

Fig. 23 is a detail front elevation, looking in the direction of the arrow 23 in Fig. 18.

Referring to the drawings, I have shown a thread grinding machine comprising a base or bed 30, a work table 31, a head stock 32, a tail stock 33, a wheel table 34, a wheel carriage 35, and a wheel head 36. The details 95 of construction of the wheel head and carriage are not set forth in detail herein, as they are substantially shown and described in my prior application, Serial No. 411,243, filed September 18, 1920.

For the purposes of this application, it is sufficient to state that the grinding wheel W (Fig. 3) is mounted on a wheel shaft 37, rotatable in bearings 38 forming a part of the wheel head 36. The head 36 is mounted for 105 angular adjustment in segmental guide-ways 39 on the front of the wheel carriage 35, the head being angularly adjusted by means of a screw 40. This angular adjustment permits the wheel to be set to correspond to the pitch of the thread to be ground. The wheel shaft 37 is rotated by a belt 42 and the wheel

carriage 35 may be adjusted toward and from the work by a hand wheel 43. (Fig. 1.)

The wheel table 34 is mounted to slide longitudinally on guide-ways 44 and 45 (Fig. 1) formed on the base 30, the table being moved longitudinally by a lead screw 46 mounted in a bearing 47 and threaded into a nut 48 (Fig. 15). The nut 48 is slideable between the guide-ways 49 and 50 and may be secured in adjustable longitudinal position therein by clamping bolts 51. The nut 48 is preferably provided with a removable inner sleeve or bushing 52 held within the nut by clamping bolts 53 and easily removed and replaced. Locking collars 54 and 55 are provided for taking up all end play in the bearing 47.

With this construction, it is evident that the position of the nut 48 in the table 34 may be changed from time to time, thus bringing the wear upon different portions of the lead screw and avoiding the disadvantage which is often encountered of concentrating the wear of the screw at one limited portion of its length. The lead screw 46 is provided with a gear 56 meshing with an idle or intermediate gear 57, which in turn is driven by a gear 58, mounted on the work spindle 60. The intermediate gear 57 is mounted upon a plate 59 which may be adjusted on the end of the base 30 to mesh with gears 56 and 58 of different sizes when desired, but I contemplate the use of very few change gears, as I consider it more desirable to provide a separate master or lead screw 46 and bushing 52 for each different pitch to be ground.

The work spindle 60 is supported in conical bearings 61 and 62 in the head stock 32 and the usual lock nuts 63 are provided for taking up end play in the bearings. A bevel gear 64 is preferably mounted on the spindle 60 and is engaged by a bevel pinion 65 mounted on a short shaft extending forward through a bearing 66 and having a hand wheel 67 at its front or outer end.

This hand wheel is used for making limited angular adjustments of the work for purposes to be hereinafter described and may be provided with suitable graduations to be read in connection with an index or pointer 68, indicating the exact amount of the angular adjustment of the work.

The work table 31 rests upon a flat finished surface of the bed 30 and is provided with a longitudinal groove or guide-way 70 (Fig. 5) closely fitting a pair of guide-blocks 71 and 72 (Fig. 4). The block 71 is pivoted at 73 to the base 30, near the left hand end of the table 31. The block 72 is pivoted at 74 to a slide 75 mounted for limited transverse movement in a recess 76 in the upper face of the base or bed 30. Adjusting screws 77 and 78 are provided by which the transverse position of the slide 75 and block 72 may be accurately adjusted. The table 31 is se-

cured to the base 30 by clamping nuts 79 and 80. Studs for these nuts are fixed in the base 30 and extend through longitudinal slots 81 and widened segmental slots 82, these slots permitting limited longitudinal adjustment of the table.

For the purposes of such longitudinal adjustments, a bracket or arm 83 is secured to the edge of the table 31 and a pair of adjusting screws 84 and 85 are threaded in bearings 86 fixed to the side of the base 30. By turning the screws 84 and 85, limited longitudinal adjustment of the table may be secured. The parts after adjustment may be securely held from displacement by tightening the binding screws 87 (Fig. 4) to bind the screws 84 and 85. This longitudinal adjustment is used merely for aligning the wheel W with the thread groove of the tap or screw to be ground and the movement does not exceed a small fraction of an inch in extent.

The preferred construction of the tail stock 33 is best shown in Figs. 18 and 22. The tail center 90 is mounted in a spindle 91, slideable in suitable bearings in the tail stock 33. A spring 92 is disposed in a recess in the spindle between a shoulder 93 thereof and a cap 94 threaded on the end of the tail stock. The spring 92 yieldingly presses the tail center towards the work.

A hand lever 95 (Fig. 18) is mounted on a fixed pivot 96 and is provided with a lug or arm 97 extending inward to engage a shoulder 98, formed in the side of the spindle or slide 91. The handle 95 thus constitutes means by which the tail spindle may be withdrawn against the pressure of the spring 92 to release the work.

A cam member 99 may be rotatably secured on the cap 94 by a screw 100 extending through a segmental slot 101 formed in the periphery of the cam member. The cam member 99 is also provided with a handle 102 and with a notch 103. When the handle 102 is swung forward the cam engages the handle 95, depressing the same and withdrawing the tail center. If the cam is advanced to its full extent, the handle 95 is received in the notch 103 and the parts will be held in this position until thereafter released by the operator.

In the operation of my improved grinding machine, I use work driving devices of novel construction which devices will now be described, particular reference being made to Figs. 9 to 14.

The usual face plate 105 is threaded on the end of the spindle 60 and is provided with a hub or extension 106 on which is mounted a ring 107 supporting a pair of work driving dogs 108. These dogs are radially adjustable on the ring 107 and are secured thereto by binding screws 109. The inner ends of the dogs are shaped to receive and

engage the shank of a tap or other article to be ground.

The ring 106 is flanged and is held against the face plate by an outer ring 110 secured 5 to the face plate by binding screws 111 and 112 (Figs. 8 and 14). A slot 113 extends nearly around the ring 110 and the binding screw 111 is shown as extending through this slot, while the screw 112 extends through 10 a hole in the ring 110 between the ends of the slot 113. A series of tapped holes 114 may be provided in the face plate to receive the screws 111 and 112.

Segmental blocks 115 and 116 (Figs. 8 15 and 12) are provided with curved ribs or projections 117 (Fig. 13) fitting the segmental slot 113. These blocks are secured in angular adjusted position by clamping bolts 118 and nuts 119 (Fig. 12). A spring handle 20 120 is secured to each block 115 or 116 and is provided with a spur 121 engaging notches 110^a formed at the outer edge of the ring 110.

A similar spring handle 122 is secured to 25 the inner ring 107, this handle being provided with a socket or recess 123 adapted to receive pins or studs 124 formed on the ends of the bolts 118 which secure the blocks 115 and 116 in position. Stops 125 and 126 30 (Figs. 8 and 11) are also slidable in the slot 113 of the ring 110 and may be clamped in position as will be hereinafter described.

In the operation of my improved machine, 35 the blocks 115 and 116 are so located that the movement of the handle 122 from one pin or stud 124 to the other will cause an angular movement of the dogs 108 exactly equal to the back lash in the connections between the work spindle and the grinding 40 wheel table. The extent of this angular adjustment of the work required with a particular set-up of the machine is determined experimentally by use of the indicating device shown in Figs. 15 to 17.

An arm 130 (Fig. 15) is fixed on the lead 45 screw nut 48 and extends forwardly and upwardly to a position for engagement by the short end of an index lever 131, pivoted at 132 on a stand 133. The stand is adjustably secured to the head stock 32 by a clamping bolt 134. A lock plate 135 is slidably mounted in guideways 136 on the head stock 32 and may be secured in adjusted position by a clamping bolt 137. An index or zero 50 line is formed on one of the guide-ways 136 as a reference mark for the index-lever 131.

In order to determine the exact amount of back lash in the connections between the spindle and the wheel table, the spindle is 55 moved in the direction in which it has been rotating until the handle 122 of the dog-supporting ring 107 is aligned with the jaws of the lock plate 135. This plate is then advanced in its guide-ways 136 until it releases the handle from the pin or stud 124.

on which it has been seated and locks it from further angular movement. The stand 133 of the index lever or pointer 131 is then adjusted so that the rear end of the pointer will be pressed against the arm 130 by the 70 pointer spring 138, while at the same time the end of the pointer co-incides with the zero mark on the guide-way 136.

The spindle 60 is then turned backward 75 or in the opposite direction to that in which it has been rotating until the lead screw 46 begins to move the nut 48, such movement being instantly indicated by movement of the pointer 131. The second sliding block 115 or 116 is then moved to bring its stud 124 into alignment with the recess in the handle 122, in which position it is then secured.

With the positions of the blocks 115 and 116 thus accurately located, it is merely necessary to swing the handle 122 from one stud 124 to the other, when the direction of the table feed is reversed to cause the grinding wheel to accurately follow the thread in both directions of table feed. If it is found that the wheel when thus adjusted engages slightly harder on one side than on the other, one of the blocks 115 or 116 may be further adjusted by moving its handle 120 95 one or more notches along the ring 110.

When adjustment is once made for a particular set-up of the machine, no further attention is necessary beyond swinging the handle 122 from one stud 124 to the other at each end of the wheel travel. The output 100 of the machine is thus greatly increased, as the usual idle return feed of the grinding wheel is entirely avoided.

When grinding certain types of thread, such as the Acme thread, it is sometimes desirable to feed the wheel sideways to widen 105 the thread groove. The stops 125 are then used to preserve the original setting so that the slides 115 or 116 may be moved the required number of notches sideways to widen 110 the thread and may then be returned to their original positions when a new thread is to be ground and widened.

It has been found desirable to drive the work spindle by a belt pulley of fairly large 115 diameter as this type of feed reduced the chatter or other irregular movements of the work, and I have shown in Fig. 1 a cone pulley 140 by which the speed may be varied, each step of the cone however being of relatively large diameter.

The face plate 105 may be provided with 120 graduations as shown in Fig. 10 and the ring 110 may have an index mark co-operating therewith to indicate the angular relation of 125 these parts. These graduations are useful when it is desired to advance the ring a certain angular amount relative to the face plate.

Referring particularly to Figs. 18 to 23, 130

I have shown a wheel dressing device by which the wheel may be dressed to restore the face of the wheel to its original shape and position. For this purpose, I provide 5 a shaft 141, (Fig. 18) one end of which is pivoted in the head stock 32 and the other end of which is supported in a bearing 142 (Fig. 23) mounted on the base 30. A binding collar 143 (Fig. 18) and a threaded 10 bushing 144 are provided for taking up end play in the shaft 141. A guide plate 145 is clamped to the shaft 141 and may be secured in any desired longitudinal position thereon by a binding screw 146. A support 147 15 (Fig. 20) extends downward from the plate 145 and is provided with an adjusting screw 148 adapted to engage the inclined face of the work table 31, supporting the guide plate in operative position.

20 The guide plate 145 is provided with a pair of guide-ways 149 and 150, equally inclined with respect to the plane of the wheel W and the guide plate is also provided with a third guide-way 151 extending parallel to 25 the axis of the wheel W. A diamond point 152 (Fig. 19) is adjustably mounted in the plane of a diagonal of the square slide 153.

In dressing a wheel, the guide-plate 145 is first adjusted longitudinally until it is centered with respect to the wheel W. The slide 30 153 is then moved back and forth along one of the guide-ways 149 or 150 to dress one side of the wheel and the slide is then reversed and moved along the other guide-way to 35 dress the opposite side of the wheel, the wheel being fed forward slightly if necessary during the wheel dressing operation.

It is often desirable to true up the extreme edge of the wheel or to provide a narrow flat face thereon and for this purpose I 40 provide the auxiliary slide block 154 in which a second diamond point 155 is adjustably mounted. The block 154 is provided with a V shaped projection 156 fitting the 45 guide-way 151. The block can thus be moved parallel to the axis of the wheel and the point 155 may be advanced to engage the edge of the wheel as desired.

My wheel dressing device is shown in the 50 drawings in operative position, but when not in use it may be swung forward and downward without removal from the machine. The device is thus always convenient for use when desired. In Fig. 4 I have shown a 55 support 160 upon which a tap may be placed in convenient position for the operator when changing the work.

Having thus described my invention and indicated the method of operation thereof, 60 it will be seen that my improved machine and method of using the same enable me to secure greatly increased production and improved results in this line of work. By setting the blocks on the face plate to correspond to the back lash of the machine, I am

able to continue the grinding operation during the movement of the grinding wheel in both directions, thus practically doubling the production over the usual type of machine in which an idle return travel is necessary. 70

My improved wheel dressing device enables me to sharpen the wheel without disturbing the adjustment of the parts, so that the sharpened wheel is immediately available for use without readjustment of the machine. 75

The hand wheel 67 on the head stock 32 is particularly useful in advancing the spindle 60 to bring the cutting face of the teeth of a tap to a horizontal position when setting up the machine, so that the work 80 table may be adjusted to accurately center the wheel in the thread of the tap. Where the taps are accurately threaded and the corresponding face of each tap is marked by some symbol as B in Fig. 9, I find it possible to successively insert a series of taps in the machine and continue the grinding operation without any resetting or adjustment of the machine for each different tap. 85

An incidental advantage of using the 90 grinding wheel to cut when moving in both directions is the correction of inaccuracies of the lead screw and gearing, which inaccuracies are found to be accurately reproduced in the thread when the grinding operation is wholly performed with the wheel moving in one direction only. When moving in both directions, the back lash of the machine transfers the inaccuracies to different 95 points in the threads on the return movement and the inaccuracies are thus largely corrected or eliminated. 100

While I have described the adjustment for back lash as being made between the work and its driving spindle, my invention and particularly my improved method of operation is not limited in its broader aspects to the provision or use of a particular adjusting device or to a particular location thereof and my invention broadly contemplates the 110 use of any suitable adjusting device by which such correction may be made at any available point between the work and the grinding wheel.

The method of operation by which I am 115 able to take successive cuts with the grinding wheel travelling in opposite directions is not claimed herein but forms the subject matter of a divisional application, Serial No. 43,418, filed by me July 13, 1925. 120

The work driving device shown particularly in Figs. 8 to 14 of the drawings is not claimed herein but forms the subject matter of a second divisional application Serial #75,201, filed by me December 14, 1925. 125

Having thus described my invention, it will be evident that changes and modifications can be made therein by those skilled in the art within the spirit and scope of my invention as set forth in the claims, and I do 130

not wish to be otherwise limited to the details herein disclosed, but what I claim is:—

1. A thread grinding machine comprising a grinding wheel, a work rotating member, connected means to rotate said member and move said wheel axially of the work, and means to adjust said connections by a predetermined amount to compensate for back lash in said connections when the direction of motion is reversed, said grinding wheel being operative to grind threads when the work is rotating in either direction.
2. In a thread grinding machine, a grinding wheel, a work rotating member, connections between said wheel and member, and a device to indicate the initial movement of the grinding wheel axially relatively to the work when the direction of wheel travel is reversed.
3. In a thread grinding machine, a grinding wheel, a work rotating member, connections between said wheel and member, and a device to indicate the initial movement of the grinding wheel axially relatively to the work when the direction of wheel travel is reversed, and means to angularly adjust the work relative to the work rotating member to compensate for said axial adjustment of the wheel.
4. In a thread grinding machine, a head stock, a work supporting spindle, a work driving member mounted thereon, means on said head to release said member from said spindle and to hold said member in fixed position, a grinding wheel, a support therefor, connections between the spindle and the wheel support, and a multiplying device to indicate initial movement of the wheel support when the back lash of said connections is taken up by reversed rotation of said spindle.
5. In a thread grinding machine, a head stock, a work driving spindle mounted therein, power means to rotate said spindle, a short shaft extending forwardly through the front of said head stock and geared to said spindle, and means on the front end of said shaft by which said spindle may be angularly adjusted.
6. In a thread grinding machine, a head stock, a work driving spindle mounted therein, power means to rotate said spindle, a short shaft mounted in said headstock and geared to said spindle, said shaft extending forwardly through the front of said head stock, and a hand wheel on said short shaft having
- graduations co-operating with a fixed index to indicate angular adjustment of said spindle.
7. In a thread grinding machine, a work table, a tail stock, a tail center, a slidable support therefor, means to yieldingly advance said support and center to operative position, means to withdraw said support, and a manually operable cam to actuate said means to withdraw said support and center and to lock said center in withdrawn position.
8. In a thread grinding machine, a work table, a tail stock, a tail center, a slidable support therefor, means to yieldingly advance said support and center to operative position, and means to withdraw said support and to retain said support in inoperative withdrawn position.
9. In a thread grinding machine, a lead screw, a wheel table, and a nut for said screw, said nut being adjustable on said table axially of said screw.
10. In a thread grinding machine, a wheel table, a lead screw, a nut for said screw, guide-ways on said table in which said nut may be adjusted axially of said screw, and means to secure said nut in adjusted longitudinal position in said guide-ways.
11. In a thread grinding machine, a lead screw, a wheel table, and a nut casing secured to said table for adjustment axially of said screw, said casing having a removable bushing fitting said screw, and means to secure said bushing in position.
12. In a grinding machine, a bed, a work supporting table, means to guide said table longitudinally on said bed, and means to adjust said table longitudinally, said means comprising a bracket on one of said parts and co-operating adjusting screws reversely mounted on the other part and engaging opposite sides of said bracket.
13. In a thread grinding machine, a bed, a work supporting table mounted thereon, said table having a longitudinally extending guide-way in its lower face, a block pivoted to said bed and fitting said guide-way at one end of said table, a second block fitting said guide-way at the opposite end of said table, a slide to which said second block is pivoted, and means to adjust said slide in said bed transversely of said table.

In testimony whereof I have hereunto affixed my signature.

JOHN BATH.
